UNITED STATES PATENT OFFICE.

GEORGE A. ROBERTSON, OF WESTMOUNT, CANADA.

CATCH-BASIN.

SPECIFICATION forming part of Letters Patent No. 642,530, dated January 30, 1900.

Application filed September 20, 1898. Serial No. 691,474. (No model.)

To all whom it may concern:

Be it known that I, GEORGE A. ROBERTSON, a subject of Her Majesty the Queen of Great Britain, residing at Westmount, Province of Quebec, Canada, have invented certain new and useful Improvements in Catch-Basins, (for which Letters Patent of the Dominion of Canada were granted September 6, 1898, No. 61,106, the application for which was filed 5 August 26, 1898, Serial No. 82,826;) and I do hereby declare the following to be a full, clear, and exact description of the invention, such as will enable others skilled in the art to which it appertains to make and use the same.

15 My invention relates to improvements in street-receivers or catch-basins, and has particular reference to that type of catch-basins which are made of a plurality of sections; and my object, briefly stated, is to provide catch- 20 basins of this type which are particularly adapted for use in cold climates, where the sewer-pipes are at a suitable depth, so as to be below the frost-line and where the catch-basins must necessarily be quite deep.

25 All sectional catch-basins for sewers as heretofore constructed, so far as I am aware, have been formed so that movements of the earth around them, due to the action of frost, has had a tendency to separate the sections 30 and to loosen the connection with the sewer-pipe. It has been proposed in such catch-basins to provide interlocking lugs on such sections; but this adds expense to the catch-basin, and, moreover, the interlocking lugs 35 are liable to become broken. There are several advantages in sectional catch-basins which make them desirable. Among these advantages are: They are easier to construct in sections and are easier transported when 40 so made. If a breakage occurs in a section the entire catch-basin is not ruined. In locating such catch-basins the lower section can be placed at the bottom of the excavation and the connection with the sewer-pipe 45 made while the workman stands inside of said lower section, after which the upper sections can be placed in position. The earth around the lower part of the catch-basin can be stamped down in place better and more solidly 50 when the catch-basin is a sectional one than when in one whole piece, because it can be done before the upper sections are put in

place, the workman standing inside the lower section, and the excavation for a sectional catch-basin does not have to be as large as 55 for an integral catch-basin of the same size, for the reason that, as above stated, the operation of making the connection with the sewer-pipe may be performed while the workman stands inside and reaching over with his 60 arms, while with an integral catch-basin the excavation must be large enough to permit the workman to stand and work outside thereof in making such connection. Another important advantage in a sectional catch-basin 65 is that when the grading of the street is changed the upper section may be removed and may be replaced by another section of greater or less height, as occasion may require, whereas when an integral catch-basin 70 is used it frequently has to be entirely removed and replaced by another or has to be reset. As above stated, however, so far as I am aware, all sectional catch-basins for sewers have been so constructed that they were liable 75 to be acted upon by the movements of earth around them to the detriment of the connections between the sections and with the sewer-pipe.

The object of my invention is to provide a 80 sectional catch-basin for sewers that will be free from any external projections that might be acted upon by the earth and of such form that no lugs or interlocking parts are necessary to insure the correct and permanent relative positions of the various sections. I attain these objects by constructing the catch-basin of a series of uniformly-tapered sections, each section being larger at the bottom than at the top, the lower section having 85 means for connecting it with a sewer-pipe and having a closed bottom of greater diameter than any other portion of the catch-basin, the upper sections being entirely free from external 90 projections.

In the drawings, in which similar numerals of reference indicate similar parts in all of the views, Figure 1 is a view showing my invention as applied. Fig. 2 is a central vertical sectional view of the same. Fig. 3 is a 100 top plan view of the trap. Fig. 4 is an elevation of the trap.

1 designates a catch-basin formed of a series of sections 2, the lower section being pro-

vided with a bottom which may be formed integral with the sides of the section or may be secured thereto to make a perfectly tight joint. The lower section is provided at one 5 side with an opening 3, to which is applied the sewer-pipe connection 4, and mounted inside of said opening 3 a trap 5 is removably secured in a suitable manner, such as by suitable inclined slideways 6, in which the trap 10 5 is adapted to be placed and be held in tight position by reason of its weight; a removable top 7 serving to close the top of the trap in an obvious manner. Each of the sections exclusive of the lower section is provided at 15 its lower end with inwardly-extending annular flanges 8, which are adapted to fit on the upper end of the next section below. The upper section has a portion of its top closed, as best shown in Fig. 2, and within the reduced opening formed and mounted on the 20 top of the upper section is the street or top section 9, having its face provided with suitable openings 10 for the passage of the drainings. If desired, the top of the section 9 may 25 be made removable, although such is not necessary.

By this construction it will be readily seen that I have provided an improved catch-basin which is extremely durable in its 30 construction and which when the grade of the street is to be changed will allow of the varying of the position of the basin without unnecessary trouble, this being accomplished by means of the addition to the basin of an 35 other section or the substitution of sections of different sizes, it being apparent that sections of various sizes may be made as may be found necessary and that one may be readily substituted for another.

40 It will now be understood that, due to the shape of the basin, any pressure of the earth against the sides will only tend to more firmly hold the upper sections upon the lower one, which latter is in practice firmly seated below the frost-line, and this is attained without the use of any locking means whatever between the sections, and owing to the fact that no interlocking devices are employed no 45

particular care is necessary when locating the upper sections, as each said section may 50 be simply placed in position and left there without rotating or using any care or effort to make the parts fit, as is necessary where interlocking lugs are used. This freedom from interlocking lugs or projections enables 55 the section below the section 9, however, to be so rotated, if necessary, on its seat as to bring the top of that section in proper position to receive said section 9, so that the face of said latter section will be held in alignment with the curb or other predetermined position, as will be clear by referring to Figs. 1 and 2.

Having thus described my invention, what I claim as new is—

65 A catch-basin comprising a series of uniformly-tapered sections, each section being larger at the bottom than at the top, the lower section having a sewer-pipe connection and a closed bottom of greater diameter than any 70 other portion of the catch-basin, the upper sections being entirely free from external projections and each of the upper sections being freely rotatable upon the section below it, each section except the lower one having an 75 annular flange fitting within the upper edge of the section on which it rests, whereby the upper sections are solely and firmly held to their seats by the pressure of the earth against their tapering sides, and whereby the 80 shape and external configuration of the catch-basin as a whole will prevent any portion thereof from being lifted by movement of the earth against the sides of any portion thereof, the upper end of the upper section having 85 a non-circular opening, and a street or inlet section fitted to said opening, whereby said street or inlet section can be rotated only with the upper tapering section.

80 In witness whereof I have hereunto set my hand in the presence of two witnesses.

GEORGE A. ROBERTSON.
